CLAIM

The ornamental design for an aerosol glass cleaner can, as shown and described.

DESCRIPTION

FIG. 1 is a front, left, top, perspective view of an aerosol glass cleaner can, showing a first embodiment of our new design;

FIG. 2 is a top plan view thereof, shown at an enlarged scale;

FIG. 3 is a front elevational view thereof, shown at an enlarged scale;

FIG. 4 is a right side elevational view thereof, shown at an enlarged scale;

FIG. 5 is a rear elevational view thereof, shown at an enlarged scale;

FIG. 6 is a bottom plan view thereof, shown at an enlarged scale;

FIG. 7 is a front, left, top, perspective view of an aerosol glass cleaner can, showing a second embodiment of our new design;

FIG. 8 is a top plan view thereof, shown at an enlarged scale;

FIG. 9 is a front elevational view thereof, shown at an enlarged scale;

FIG. 10 is a right side elevational view thereof, shown at an enlarged scale;

FIG. 11 is a rear elevational view thereof, shown at an enlarged scale; and,

FIG. 12 is a bottom plan view thereof, shown at an enlarged scale.
